(57) **CLAIM**

The ornamental design for a makeup case with LED mirror, as shown and described.

DESCRIPTION

FIG. 1 is a perspective view of the makeup case with LED mirror showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with numeric 9 in FIG. 1; and,

FIG. 10 is a perspective view thereof when the lid of the makeup case with LED mirror is open.

The broken lines shown in the drawings represent portions of the makeup case with LED mirror that form no part of the claimed design.

1 Claim, 10 Drawing Sheets
